HEAT EXCHANGER

George A. Worn, Greenwich, Conn., and George W. Evans, Jr., Teaneck, N. J., assignors to The Lummus Company, New York, N. Y., a corporation of Delaware

Application January 24, 1947, Serial No. 724,164

6 Claims. (Cl. 257—32)

1

This invention relates to improvements in a subcooler construction for heat exchangers of the shell-and-tube type.

A certain type of subcooler construction includes a tubular longitudinal baffle of the "bundle wrapper" type. In a heat exchanger having a plurality of tube passes and wherein a heated fluid is passed through the shell and a cooling fluid is passed through the tubes, such a baffle is employed to conduct the shell-side fluid, in its final cooling stage, along the coldest tubes of the exchanger. For that purpose, the baffle is arranged to enclose a group of tubes included in the first pass and to conduct the shell-side fluid along the enclosed tubes to a discharge point remote from the point where the fluid enters the baffle. For discharge of the fluid, the baffle is provided with a transverse nozzle which is attached to the baffle and projects outwardly through another nozzle welded to the side of the shell. Such a construction greatly complicates the manufacture and servicing of the exchanger. The discharge nozzle cannot be attached to the baffle until the latter has been inserted into the shell, along with the tube bundle, nor can the bundle and the baffle be removed without first breaking the connection between the nozzle and the baffle. Owing to the fact that the space available for making and breaking the connection is quite limited and difficult to reach, both operations are extremely laborious and time consuming.

A copending application of George A. Worn, Serial No. 655,824, filed March 20, 1946, discloses, in a vertical heat exchanger having a channel structure at the upper end of the shell and a bundle of U-tubes depending from said structure, a subcooler feature having a discharge connection embodied within the channel structure and clear of the shell in order to facilitate assembly and disassembly of the exchanger. An important object of the present invention is to provide, in a vertical heat exchanger having the channel at the lower end of the shell and a tube bundle projecting from the channel upwardly within the shell and provided with a floating head, an improved subcooler construction also having a discharge connection embodied in the channel and affording the aforesaid advantages in assembly and disassembly.

A further object of the invention is to provide in such a heat exchanger an improved subcooler baffle construction.

A still further object of the invention is to provide, in combination with the subcooler baffle construction, an improved vent feature.

2

Further objects and advantages of the invention will appear from the following description taken in connection with the accompanying drawing.

5 In the drawing:

Fig. 1 is a vertical longitudinal sectional view of a heat exchanger embodying the invention, the section being on the line 1—1 of Fig. 2 and parts being broken away;

10 Fig. 2 is a horizontal section on the line 2—2 of Fig. 1; and

Fig. 3 is a detail sectional view on the line 3—3 of Fig. 2.

The structure of the heat exchanger includes 15 a vertical shell 1 having an outwardly extending flange 2 at its lower end. As shown, said flange may be formed on an annular section 3 welded to the body of the shell as at 4. The upper end of the shell is dome-shaped. A nozzle 5 for entry 20 of shell-side fluid is welded to the shell at a high point of the latter.

A channel structure 6 is secured to the lower end of the shell and includes a flat upper wall portion and a depending annular body portion 25 7. Said upper wall portion forms a tube sheet 8 and an outwardly extending flange 9 underlying the shell flange 2. A gasket 10 is interposed between the flanges 2 and 9 and bolts 11 pass through said flanges, outwardly of the gasket, and releasably secure the channel structure to the shell. A closure plate 12 is fitted within the lower portion of the body of the channel and secured by any suitable locking and sealing structure, such as that disclosed in Patent No. 2,268,367 of Gertzon, for example. In such case the channel wall is formed with an internal groove 13. A split locking ring 14 has a peripheral portion thereof projecting into said groove, and a backing ring 15 is fitted within the locking ring to hold the latter expanded. The closure plate is peripherally recessed to accommodate said rings. The under faces of the channel and the closure plate are substantially flush and a gasket 16 overlaps both of said faces. A pair of concentric clamping rings 17 and 18 bear against the gasket. The ring 17 is secured to the channel by bolts 19, and the ring 18 is secured to the closure plate by bolts 20. The particular sealing means disclosed however, forms no part of the present invention.

30 A partition 21 divides the channel space into two compartments 22 and 23, respectively. An inlet nozzle 24 welded to the channel opens into the compartment 22, and an outlet nozzle 25 welded to the channel opens from the compartment 23. A bundle of straight vertical tubes 26

extend from the channel tube sheet 8 upwardly within the shell. These tubes have their lower ends rolled into the tube sheet 8, and a floating head structure 27 is connected to the upper ends of the tubes. The floating head structure comprises a flat bottom wall forming a tube sheet 28 into which the upper ends of the tubes are rolled, and an upstanding annular wall 29. A closure plate 30 is fitted into the upper portion of the wall 29 and secured and sealed by means similar to that employed for securing and sealing the channel closure plate 12. In the drawing the parts of the floating head sealing means corresponding to those of the channel sealing means are correspondingly numbered, and primed. Some of the tubes opening into the floating head lead from the inlet compartment 22 of the channel and constitute the first tube pass, and others of the tubes lead from the floating head to the channel outlet compartment 23 and constitute the second and final tube pass. Of course, the number of passes may exceed two.

The subcooler structure includes an upstanding tubular baffle 31. In the present instance this baffle surrounds a portion only of said tubes of the first pass. However, it may be constructed and arranged to surround all of the tubes, of said pass. The baffle is welded, as at 32, entirely around its lower edge to the upper face of channel tube sheet 8, and the upper end of the baffle is spaced below the floating head tube sheet 28. Transverse baffles 33 in vertically spaced staggered arrangement are provided within the baffle 31. A depending tubular baffle 34, larger than the baffle 31, surrounds the latter and affords substantial flow space therebetween. Baffle 34 is welded, entirely around the upper edge thereof, to the under face of the floating head tube sheet 28, as at 35. The lower end of the baffle is spaced above the channel tube sheet 8. In the present instance the baffles 31 and 34 are of segmental form in cross-section but they may be of other form.

The provision of two tubular baffles in telescoped arrangement avoids the necessity of an expansion joint connection with the floating head, entailed by employment of a single baffle. Such a joint is difficult to reach and repair in case of rupture thereof and requires disassembly of the exchanger whereas the double baffle feature of our invention enables the floating head to rise and fall as the tubes expand and contract without strain upon any connection.

Another feature of our invention is the provision for discharge of the shell-side fluid from the interior of the inner tubular baffle 31. For that purpose, the channel structure 6 embodies a discharge conduit which is independent of the shell. This conduit is defined by a vertical port 36 in the tube sheet 8, a lateral port 37 in the annular wall 7 of the channel, and a hood-shaped element 38 disposed in the angle between the tube sheet and the channel wall. This element has a U-shaped upper edge welded to the tube sheet around the margin of the port 36, and a U-shaped vertical edge welded to said channel wall around the port 37. An elbow connection is thus formed for passage of fluid from the bottom of the space surrounded by the baffle 31 to the port 37. A nozzle 39 is welded to the wall 7 to receive the fluid passed through the port 37 and discharge it from the exchanger.

Another feature of our invention is a provision for venting the space within the upper portion of the outer tubular baffle 34. For that purpose,

a vertical vent pipe 40 has its lower end rolled into an aperture in the lower tube sheet 8 and extends upwardly to a point near the upper tube sheet 28. The lower tube sheet has a counterbore 41 into which the lower end of the vent pipe opens, and a plug 42 is screwed into the lower end of said counterbore. A vent passage 43 leads from the counterbore laterally outwardly through the tube sheet to the outer edge of flange 9. Thereby said upper portion of the baffle space is vented through a passage which is also independent of the shell.

In operating the exchanger heated fluid in either vapor or liquid phase enters the shell through the nozzle 5 and cooling fluid enters the tubes of the first pass through the nozzle 24 and the channel compartment 22 and flows upwardly through the tubes of said pass to the floating head and thence downwardly through the tubes of the second pass to the channel compartment 23 and out through the nozzle 25. The shell-side fluid introduced through the shell nozzle 5 passes downwardly around the tubes of the second pass and is thereby subjected to its first cooling stage. Thence the shell-side fluid, in liquid phase, passes upwardly between the tubular baffles 31 and 34 into the upper end of the inner baffle 31 and downwardly through the latter. Thereby said fluid is subcooled by contact with the coldest tubes of the bundle.

The subcooled liquid is then discharged through the port 36, the elbow connection 38 and the nozzle 39. Other arrangements of flow of liquid can be made if desired. Venting of the space within the upper portion of baffle 34, through pipe 40 and passage 43, prevents an air or vapor trap which would impede flow into the subcooler baffle 31.

The tube bundle and the shell may be readily separated for servicing. After release of the bolt connections 11 the channel and tube bundle, together with the floating head, may be withdrawn through the lower end of the shell, or, the shell may be withdrawn from the bundle. Since the discharge connections for the subcooler and for the vent are both embodied in the channel structure and are disposed entirely clear of the shell they form no obstruction to separation of the bundle and the shell.

While the invention has been shown and described in connection with a subcooler feature its utility is by no means limited to a subcooler.

It is, of course, to be understood that the present disclosure of our invention is merely illustrative and in nowise limiting and that the invention comprehends such modifications and adaptations as will come within the scope of the following claims.

We claim:

1. In a heat exchanger including a vertical shell having a fluid inlet, a vertical tube bundle within the shell and means for directing fluid in a plurality of passes through the tubes of the bundle and comprising a channel structure at the lower end of the tube bundle and releasably connected to the shell and including a tube sheet for the bundle, and a floating head connected to the upper end of the bundle; the improvement comprising a tubular baffle borne by and extending upwardly from said tube sheet and surrounding tubes of one of said passes and terminating below said floating head, said baffle being open at its upper end only for admission of shell-side fluid, a tubular baffle borne by and depending from said floating head and tele-

scoped over a substantial length of the first-mentioned baffle, with flow space therebetween, and terminating above said tube sheet, the second-mentioned baffle being open at its lower end only for admission of shell-side fluid and being movable vertically relatively to the first-mentioned baffle by movement of the floating head in response to expansion and contraction of the tubes, said baffles defining a passage to conduct shell-side fluid upwardly therebetween and thence downwardly along the tubes within the inner one of the baffles and said channel structure having a conduit therein independent of the shell and arranged to conduct said shell-side fluid from the lower end of said inner baffle to the exterior of the heat exchanger, and a vent pipe extending from said tube sheet upwardly within one of said baffles to a point adjacent the floating head, the channel structure having a vent passage leading from said pipe to the exterior of the exchanger.

2. In a heat exchanger including a vertical shell having a fluid inlet, a vertical tube bundle within the shell and means for directing fluid in a plurality of passes through the tubes of the bundle and comprising a channel structure at the lower end of the tube bundle and releasably connected to the shell and including a tube sheet for the bundle, and a floating head connected to the upper end of the bundle; the improvement comprising a tubular baffle borne by and extending upwardly from said tube sheet and surrounding tubes of one of said passes and terminating below said floating head, said baffle being open at its upper end only for admission of shell-side fluid, and a tubular baffle borne by and depending from said floating head and telescoped over a substantial length of the first-mentioned baffle, with flow space therebetween, and terminating above said tube sheet, the second-mentioned baffle being open at its lower end only for admission of shell-side fluid and being movable vertically relatively to the first-mentioned baffle by movement of the floating head in response to expansion and contraction of the tubes, said baffles defining a passage to conduct shell-side fluid upwardly between the baffles and thence downwardly along the tubes within the inner one of the baffles and said channel structure having a conduit therein independent of the shell and arranged to conduct said shell-side fluid from the lower end of said inner baffle to the exterior of the heat exchanger.

3. In a heat exchanger including a vertical shell having a fluid inlet, a vertical tube bundle within the shell and means for directing fluid in a plurality of passes through the tubes of the bundle and comprising a channel structure at the lower end of the tube bundle and releasably connected to the shell and including a tube sheet for the bundle, and a floating head connected to the upper end of the bundle; the improvement comprising a tubular baffle borne by and extending upwardly from said tube sheet and surrounding tubes of one of said passes and terminating below said floating head, said baffle being open at its upper end only for admission of shell-side fluid, a tubular baffle borne by and depending from said floating head and telescoped over a substantial length of the first-mentioned baffle, with flow space therebetween, and terminating above said tube sheet, the second-mentioned baffle being open at its lower end only for admission of shell-side fluid and being movable vertically relatively to the first-mentioned baffle

by movement of the floating head in response to expansion and contraction of the tubes, said baffles defining a passage to conduct shell-side fluid upwardly therebetween and thence downwardly along the tubes within the inner one of the baffles and said channel structure having a conduit therein independent of the shell and arranged to conduct said shell-side fluid from the lower end of said inner baffle to the exterior of the heat exchanger, and a vent conduit independent of the shell and leading from the space within the upper end of the outer one of said baffles to the exterior of the exchanger.

4. In a heat exchanger including a vertical shell having a port opening to the exterior of the exchanger, a vertical tube bundle within the shell and means for directing fluid in a plurality of passes through the tubes of the bundle and comprising a channel structure at the lower end of the tube bundle and releasably connected to the shell and including a tube sheet for the bundle, and a floating head connected to the upper end of the bundle; the improvement comprising a tubular baffle borne by and extending upwardly from said tube sheet and surrounding tubes of one of said passes and terminating below said floating head, and a tubular baffle borne by and depending from said floating head, telescoped over a substantial length of the first-mentioned baffle and terminating above said tube sheet, the first-mentioned baffle being open at its upper end to the interior of the second-mentioned baffle and the second-mentioned baffle being open at its lower end only to the interior of the shell and being movable vertically relatively to the first-mentioned baffle by movement of the floating head in response to expansion and contraction of the tubes, said baffles defining therebetween a conduit open at its lower end to the shell space exterior to the baffles and open at its upper end to the interior of the inner one of the baffles, and said channel structure having a conduit therein independent of the shell and open at one end to the space within the lower end of said inner baffle and open at its opposite end to the exterior of the heat exchanger.

5. In a heat exchanger including a vertical shell having a fluid inlet, a vertical tube bundle within the shell and means for directing fluid in a plurality of passes through the tubes of the bundle and comprising a channel structure at the lower end of the tube bundle releasably connected to the shell and including a tube sheet for the bundle, and a floating head connected to the upper end of the bundle; the improvement comprising a tubular baffle borne by and extending upwardly from said tube sheet and surrounding tubes of one of the passes and terminating below said floating head, a tubular baffle borne by and depending from said floating head telescoped over a substantial length of the first-mentioned baffle, with flow space therebetween, and terminating above said tube sheet, the first-mentioned baffle being open at its upper end to the interior of the second-mentioned baffle and the second-mentioned baffle being open at its lower end only to the interior of the shell and being movable vertically relatively to the first-mentioned baffle by movement of the floating head in response to expansion and contraction of the tubes, said baffles defining therebetween a conduit open at its lower end to the shell space exterior to the baffles, and open at its upper end to the interior of the inner one of the baffles, and a conduit leading from the

lower portion of the space within the inner baffle to the exterior of the exchanger.

6. In a heat exchanger including a vertical shell having a fluid inlet, a vertical tube bundle within the shell and means for directing fluid in a plurality of passes through the tubes of the bundle and comprising an externally cylindrical channel structure at the lower end of the tube bundle releasably connected to the shell and including a tube sheet for the bundle, and a floating head connected to the upper end of the bundle; the improvement comprising a tubular baffle borne by and extending upwardly from said tube sheet and surrounding tubes of one of the passes and terminating below said floating head, a tubular baffle borne by and depending from said floating head and telescoped over a substantial length of the first-mentioned baffle, with flow space therebetween, and terminating above said tube sheet, the first-mentioned baffle being open at its upper end to the interior of the second-mentioned baffle and the second-mentioned baffle being open at its lower end only to the interior of the shell and being movable vertically relatively to the first-mentioned baffle by movement of the floating head in response to ex-

pansion and contraction of the tubes, said baffles defining therebetween a conduit open at its lower end to the shell space exterior to the baffles and open at its upper end to the interior of the inner one of the baffles, a conduit independent of the shell and within the cylindrical confines of the channel structure and leading from the lower portion of the space within the inner baffle through the channel structure to the outer side wall of the latter, and a nozzle borne by and extending outwardly directly from said wall and continuing said conduit to the exterior of the exchanger.
